UNITED STATES PATENT OFFICE.

GEORGE T. JACOBS, OF WASHINGTON, DISTRICT OF COLUMBIA, ASSIGNOR
OF ONE-HALF TO DANIEL WILLIAMS, OF SAME PLACE.

DESIGN FOR A SPOON.

SPECIFICATION forming part of Design No. 22,718, dated August 22, 1893.

Application filed July 14, 1893. Serial No. 480,537. Term of patent 3 $\frac{1}{2}$ years.

To all whom it may concern:

Be it known that I, GEORGE T. JACOBS, a citizen of the United States, residing at Washington, in the District of Columbia, have invented and produced a new and original Design for Spoons; and I do hereby declare the following to be a full, clear, and exact description of the same, reference being had to the accompanying drawing, forming a part thereof, which represents a front view of a spoon, showing my design.

The leading feature of my design consists in raised work surface in bowl portion of the spoon which when viewed in elevation represents the badge of the Grand Army of the Republic and the Woman's Relief Corps of the same society.

A represents the handle of the spoon which is composed of cross sabers with the guard or

shield portions joined and with the points crossing and having the bowl portion connected therewith. Within the oblong or elliptical space formed by the cross swords is the outline of a building or a representation of the Capitol building of the United States. In the bowl portion B, are formed the figures representing the badge of the Grand Army of the Republic and the Woman's Relief Corps of the same society.

What I claim is—

The design for spoons herein shown and described.

In testimony whereof I affix my signature in presence of two witnesses.

GEORGE T. JACOBS.
